UNITED STATES PATENT OFFICE.

EDWARD A. UEHLING, OF PASSAIC, NEW JERSEY.

ANNEALING APPARATUS.

SPECIFICATION forming part of Letters Patent No. 760,825, dated May 24, 1904.

Application filed December 9, 1903. Serial No. 184,416. (No model.)

To all whom it may concern.

Be it known that I, EDWARD A. UEHLING, a citizen of the United States of America, and a resident of Passaic, Passaic county, New Jersey, have invented certain new and useful Improvements in Annealing Apparatus, of which the following is a specification, illustrated by the accompanying drawings.

The casting of slag or cinder from blast-furnaces into the form of brick or building-block has proved to be a very useful and remunerative way of disposing of this by-product; but owing to the cost of manufacturing these brick or blocks by the methods heretofore in use, which necessitated frequent handling and very considerable time, to say nothing of the expense of running a separate furnace to heat the annealing-ovens, this method of disposing of the slag has not been much used.

The object of this invention is to overcome the above-mentioned and other difficulties and to enable the production of the brick or building-blocks in a rapid and economical manner.

In the device here shown the molding of the brick or building-blocks and their annealing is carried out at one and the same time, whereby many advantages are attained, besides which the bricks are annealed by means of their own latent heat.

In the drawings, Figure 1 is a plan view of the apparatus, the furnace being shown partly broken away; Fig. 2, a side elevation of the furnace on the plane 2 2 of Fig. 1; Fig. 3, a side elevation of the annealing-car, partly in section; and Fig. 4, a plan view of the car.

This improved apparatus is shown as used in conjunction with an annealing-furnace, where brick or blocks of cinder or slag are made, but it is no way limited to use with the furnace shown, for, as will hereinafter be described, the annealing process can be carried out without the use of any furnace whatsoever.

The annealing-car *b* consists of an ordinary flat-car suitably mounted on wheels to run upon the tracks or ways *c*. The bottom of this car is covered with a layer of fire-brick or other suitable fireproof material *d*. Upon

this floor is erected an open box composed of metal plates *e*. The ends of each of these plates are provided with the lugs *f*. Each of these lugs have tapering holes *h* within them adapted to receive the wedges *g*. In this manner when the plates *e* are placed in an upright position, so that their edges overlap one another, and the wedges *g* are driven into the holes *h* the box becomes rigid and stands upright upon the flooring *d*. Within the box is then placed an open frame, which is composed of four separate plates *l*, extending the height of the box. Each of these plates is provided with braces *m* to hold them in position away from the sides of the box. Within the frame thus formed are placed the longitudinal plates *k* and the short transverse plates *j*, which are secured to the open frame by means of projections upon the plates *l*, which coöperate with recesses in the plates *j* and *k*. The longitudinal and transverse plates are secured one to the other in a similar manner. This invention is by no means limited to this particular manner of fastening the plates to each other, as any means may be adopted to attain this result, the object being to have the plates easily and readily removable, so that the plates and the box itself may be taken completely apart and the parts again readily reassembled.

Near the upper portion of the plates *j* are projecting beads *t*, cast integral with the plates. These beads extend the entire length of each of the transverse plates *j* and are adapted to hold the horizontal plates *u*, as shown in Fig. 3. These horizontal plates *u* are rectangular in shape and adapted to cover each one of the rectangular openings formed by the plates *j* and *k*. Each of the plates *u* is provided with an opening *w*, which is drilled approximately in the center of the plate.

The manner in which this apparatus may be used is as follows: The plates *e* are erected upon the flooring *d*, so that their edges overlap, and the wedges *g* are driven into the holes *h*, and the box then becomes rigid. The plates *l*, which carry the braces *m*, are then placed within the box, forming an open frame. Within the frame are placed the plates *j* and *k*, which plates are retained in any desired

fixed position, either by the method shown or in any other way best suited. The molten slag or cinder is then poured into the box, the molten matter filling all the openings between the transverse and longitudinal plates to a height approximately the same as the height of the beads *t*, the plates *u* are then put in position, and the molten slag is then poured between the braces *m* until all the interstices between the braces are completely filled. It will therefore be seen that by means of the plates *l* and the braces *m* it is possible to obtain a covering for the annealing-blocks, which has the same amount of heat as the blocks themselves, and therefore will prevent the blocks from cooling too rapidly by having these coverings brought directly in contact with the outer air. The orifices *w* in the center of the plates *u* are adapted to allow any of the molten slag to rise above the height of the beads *t* without dislodging the plates.

In conjunction with this annealing-car is shown a furnace in which it may be used; but, as before stated and as will be seen by the drawings, the process of annealing can be carried out without the use of any other means than the car itself.

In Fig. 1 is shown a cinder-car *a*, adapted to transport the slag from the blast-furnace and also to discharge the slag into the annealing-car *b*.

Adjacent to the cinder-car *a* is the shed *n*, through which runs the tracks or ways *c*, on which the annealing-car is carried. Within the shed and bridging the track *c* is the annealing-furnace *o*. (Shown in Fig. 1 partly broken away.) This furnace is open at both ends to permit the car *b* to travel through it from end to end. Suspended in any suitable manner within the shed is the crane *p*, which travels transversely across the shed, besides which it is capable of longitudinal movement along the entire length of the shed *n*. Parallel to the track *c* and within the shed *n* are two other tracks *q* and *r*, the track *r* extending outside of the shed to the point where the bricks or building-blocks may be conveniently delivered when annealed. Upon these tracks *q* and *r* run flat-cars adapted one to receive the component parts of the box on the annealing-car and the other to receive the annealed blocks or bricks.

The operation of this device is as follows: The slag carried in the cinder-car *a* is brought into the position shown in Fig. 1 and its contents are discharged into the annealing-car *b*. The car *b* thus filled is then run along the track *c* either by gravity, by having the track inclined, or by any other appropriate device until the car is passed into the furnace *o* and assumes a position within the furnace, as shown in dotted lines in Fig. 1. Other similar cars are then filled and passed into the furnace until the furnace is filled with these

annealing-cars. The length of the furnace is proportional to the time which the annealing process takes and to the length of the cars—that is to say, that if, for example, the bricks can be annealed in twenty-four hours and the output of slag is ten cars for twenty-four hours, each car occupying ten feet of track, then the length of the furnace need be one hundred feet to accommodate such an output. When the material in the first car has been annealed, the car is run out of the furnace under the traveling crane *p*. The wedges *g* are removed and the various plates forming the box upon the car are carried by the crane and set upon the flat-car on the track *q*. The crane then lifts from the car *b* the annealed bricks or blocks and sets them upon the flat-car on the track *r*, which transports them to where they are to be delivered. The car on the track *q*, loaded with the various parts of the annealing-box, is then moved to a more convenient position near the cinder-car, the crane lifts the frame of the annealing-car *b* and carries it to a position adjacent to the car carrying the parts of the box, and the box is readily reassembled upon the car *b* and once more is placed before the cinder-car in a position to be refilled, and the operation repeated.

The plates composing the sides of the box forming the annealing-car and the various partition-plates within the box are preferably made of cast-iron, cast-steel, or other suitable material that will retain its position without warping when subjected to the heat of the molten slag.

Without describing the many modifications of which this invention is capable, what I claim as the novel and characteristic features of this my invention are the following:

1. In an annealing apparatus, the combination of a car adapted to convey annealed material, said car being provided with a fire-proof floor, an open metal box erected upon said floor, means for dividing a part of the interior of said box into rectangular portions, means for filling said portions with molten material to be annealed, means for substantially covering said rectangular portions with an envelop of the said molten material, and means for discharging the contents of said car, substantially as set forth and described.

2. An annealing apparatus consisting of a car suitably mounted upon wheels, removable plates, resting upon the floor of said car and forming, when in position, an open box upon said floor, longitudinal and transverse plates adapted to form a series of receptacles within said box, means for retaining said plates in position, means for preventing said plates from coming in contact with the sides of said box, means for filling each of said receptacles with the molten material to be annealed, means for covering each of said rectangular recepta-

cles, and means for removing the contents of said receptacles when the process of annealing is completed, substantially as set forth.

3. An annealing-car consisting of a flooring 5 of fireproof material, an open box erected upon said flooring, the sides of said box being composed of separable metal plates, means for interlocking said sides together, an open metal frame adapted to be placed within said box, re- 10 movable metal partition-plates adapted to be placed within said frame, means for retaining said partition-plates in any desired position within said frame, wheels suitably attached to and adapted to support said car and tracks 15 or ways coöoperating with said wheels constituting means for moving said car substantially as set forth and described.

4. In an annealing-car, the combination of a flooring of fireproof material, an open box 20 erected upon said flooring composed of separable metal plates, means for interlocking said plates in position, an open frame adapted to be placed within said box, longitudinal and transverse partition-plates fitting within said 25 frame, means for retaining said plates in position, means for filling the openings between said plates and the openings within said frame with material to be annealed, removable cover- 30 plates coöoperating with said partition-plates, and means for retaining said cover-plates in

position above said flooring, substantially as set forth and described.

5. In an annealing apparatus, the combination of a furnace, tracks or ways extending through said furnace, a car adapted to contain 35 material to be annealed, movable upon said tracks, a box composed of separable metal plates erected upon said car, means for filling said box with molten material to be annealed, means for separating and removing the separable parts of said box and means for removing the annealed material from said car substantially as set forth.

6. An annealing apparatus consisting of a car movable upon tracks or ways, said car being provided with a fireproof floor, a metal box composed of separate plates, provided with interior partition-plates, erected upon said floor, means for filling said car with molten material to be annealed, means for 45 separately removing the separate constituent parts of said box and said plates, and means for removing the annealed material from said car, substantially as set forth and described.

Signed this 7th day of December, 1903, at 55
New York city.
